UNITED STATES PATENT OFFICE.

ROBERT H. MOORE, OF CHICAGO, ILLINOIS, ASSIGNOR TO AMERICAN CREOSOTING COMPANY, OF CHICAGO, ILLINOIS, A CORPORATION OF INDIANA.

CAR-UNLOADING DEVICE.

1,028,768.

Specification of Letters Patent. Patented June 4, 1912.

Application filed November 10, 1911. Serial No. 659,639.

To all whom it may concern:

Be it known that I, ROBERT H. MOORE, of Chicago, in the county of Cook and State of Illinois, have invented certain new and 5 useful Improvements in Car-Unloading Devices; and I do hereby declare the following to be a full, clear, and exact description of the invention, such as will enable others skilled in the art to which it appertains to 10 make and use the same.

The object of this invention is to provide simple and highly efficient means for unloading cars, trams or trucks, and is especially designed for use in connection with tie or 15 timber treating plants or machinery, the contents of the cars being removed therefrom and discharged in bulk.

The invention will be hereinafter fully set forth and particularly pointed out in the 20 claims.

In the accompanying drawings, Figure 1 is an elevation showing my improvement applied to a tie adzing and boring machine. Fig. 2 is a view at right angles to Fig. 1. 25 Fig. 3 is an enlarged sectional view through a portion of one of the cradle arms. Fig. 4 is a view in perspective with parts omitted.

Inasmuch as my present invention is primarily designed for timber treating plants 30 it will be described accordingly, but it is to be understood that the use of the invention is not restricted, since it may be employed to advantage generally in unloading cars or trams.

Referring to the drawings, 1 designates a car or buggy of known construction, such, for instance, as shown in Letters Patent No. 805,214 issued to C. B. Lowry and R. Bernhard November 21, 1905. These cars have 35 carrying wheels 2 which are designed to travel on suitable track rails 3, and each car is preferably provided with bails 4 which are detachably secured to the upwardly extended ends of the car sills. The cars are 40 usually relatively short so that the ties or timbers project beyond the ends thereof.

5 designates an inclined way above and to one side of track rails 3, such way leading to a platform 6 of an adzing and boring 45 machine, conventionally indicated at 7, Fig. 1. This machine and its platform are higher than the track rails, and my invention is intended to effect the raising and discharge of the timbers from the cars to this receiving 55 platform. For this purpose I employ a

cradle which is movable at right angles to the track rails and which is so located with reference to the inclined way that as it is moved upwardly it will remove the load from the car and dump it on to the way. 60 The cradle is shown as composed of two arms 8 each of which is pivoted at 9 at points adjacent the upper ends of the inclined way. To accommodate these arms and allow them to intersect the track rails 3, the latter are cut-out, and these cut-outs are normally filled by small rail sections 10 carried by the cradle arms. The latter, and hence the cut-outs, are such distances apart that when a car is on the track between the cut-outs the ties or timbers on the car will intersect the planes of the cradle arms so that as the latter are raised they will engage and lift the timbers and as they swing on their pivots they will gradually assume the inclined position shown in Fig. 1 and thereby discharge the timbers on the inclined way. 70 To prevent the cars from being displaced in the lifting of the timber therefrom hooked-lugs 12 carried by the cars are designed to engage guard rails 13 adjacent to track rails 3 between the cut-outs thereof, such lugs and guard rails being substantially the same as shown and described in the before noted patent. 75

It is understood, of course, that in handling timber the bails 4 are removed for unloading.

Any suitable means may be employed for raising the cradle; that shown comprises 90 hoisting cables 14 passed over suitable pulleys supported by a super-structure 15. After the load is discharged the cradle is lowered by gravity.

I claim as my invention:—

1. A device for unloading a car on a track comprising a cradle movable on a fixed plane transversely of a fixed track in proximity to and beyond the ends of a car thereon for raising the load bodily from the car, and a platform upon which the load is discharged. 100

2. A device for unloading a car on a track comprising a cradle movable on a fixed plane transversely of a fixed track in proximity to and beyond the ends of a car thereon and designed to engage and raise the load from the car without disturbing the latter and discharge the load at one side of the track. 105

3. A device for unloading a car on a track comprising a cradle pivotally mounted at 110

one side of a fixed track and movable on a fixed plane transversely of the latter and in proximity to the ends of a car thereon, means for raising the cradle and turning it 5 on its pivot, and a platform upon which the cradle discharges the load raised thereby from the car.

4. In combination with a fixed track having cut-outs and a car designed to be located between said cut-outs, a cradle pivotally mounted at one side of the track and fitting in said cut-outs, said cradle in its upward travel being designed to raise the contents from the car, and a platform upon 15 which the cradle discharges.

5. In combination with a fixed track having cut-outs, and a car designed to be located between said cut-outs, a cradle pivotally mounted at one side of the track and fitting in said cut-outs, said cradle in its upward travel being designed to raise the contents from the car, and means for retaining 20 the car on the track while the cradle is lifting the load therefrom.

6. In combination with a railway track, 25 two spaced apart arms movable transversely of and designed to intersect the track rails, said arms being pivoted at one end at one side of the track, a platform adjacent to the pivoted ends of said arms, and means for 30 raising the arms and turning them on their pivots, said arms being designed to engage timber projecting beyond the ends of a car on said track rails.

7. In combination with track rails having 35 cut-outs, two arms pivoted adjacent to the track and having rail sections designed to fit in said cut-outs, a platform leading from the pivoted ends of said arms, and means for 40 raising said arms and turning them on their pivots.

In testimony whereof, I have signed this specification in the presence of two subscribing witnesses.

ROBERT H. MOORE.
